PLAYROOM

Donald M. Warren, West Lafayette, Ind.

Application January 2, 1934, Serial No. 704,830

2 Claims. (Cl. 46—21)

This invention relates to improvements in play rooms and more particularly to doll-house-like simulations of various rooms in which children may arrange toy furniture. The main objects of the invention are to provide a play room construction of the type referred to which may be produced and sold at low cost without making the room too small to accommodate toy furniture and other equipment of fair size.

10 Another object of the invention is to provide a play room construction of the type referred to which may be made of inexpensive light material, for example, cardboard of a fairly stiff variety, while at the same time producing a quite rigid 15 structure; to provide an arrangement in which a plurality of the rooms may advantageously be stacked one upon the other; and in general, it is the object of the invention to provide an improved play room structure of the type referred to.

20 Other objects and advantages will be understood by reference to the following specification and accompanying drawing in which there is illustrated a play room embodying a selected form of the invention.

25 In the drawing, Fig. 1 is a perspective; Fig. 2 is a perspective of fragmentary portions of the construction in detached relation; Fig. 3 is a fragmentary plan; and

30 Figs. 4 and 5 are end and front views respectively showing a plurality of the room structures stacked one on the other.

Referring now to the drawing, the improved play room structure includes a box section 6 which is preferably one portion of a box, for example, the bottom section, in which the play room structure is adapted to be packaged for transportation and sales purposes. The box section 6 embodies a bottom wall 7 and depending edge flanges 8. The box section is inverted and a side 35 wall 9 and end walls 10, 10 respectively are arranged on the inverted box bottom.

40 The box bottom is provided with a series of openings such as indicated at 11 in alignment with the bottom edges of the respective walls 9 and 10, 10, the openings being preferably of triangular or other shape which provides pointed or other similar end portions 12, 12, for a purpose which will presently appear. The side and end walls are each provided with a series of ears 13 45 which depend from their lower edges and are adapted to project through the respectively aligned openings 11, 11. The ears 13 are of such width that they will be a force fit through the longest dimensions of the openings 11 and the pointed or 50 similarly shaped corner portions of these openings

will tend to effectively grip the tongues so as to hold the side and end walls in assembled relation to the box bottom. It has been found that tongues and openings of the type referred to are particularly satisfactory because of the effective 5 gripping of the tongues, with the result that the component parts of the play room will not readily become separated.

The side wall 9 and the rear edges of the respective end walls 10, 10 are also connected by 10 means of openings 11 in the side wall and tongues 13 projecting from the rear edges of the respective end walls, these tongues and openings being similar to those just described for connecting the 15 respective walls to the bottom.

In some instances, it is preferred to arrange the end walls 10, 10 at an angle to each other, as clearly shown in Fig. 1. By reference to Fig. 3, it will be seen that by so arranging the end walls, the rearwardly projecting tongues 13 thereof will 20 be disposed at oppositely inclined angles relative to the side wall 9, so that in addition to the normal gripping action of the openings on the tongues 13, there will be a lock incident to the inclined 25 relation of the tongues. This feature of locking the parts together will be especially advantageous where conventional tongue and slot connections are used for connecting the various parts.

On the interior sides of the walls 9 and 10, 10, 30 representations of room furnishings and trim may desirably be supplied. For example, panel moldings, as indicated at 14, and base-board and cove moldings, as indicated at 15 and 16 respectively, may be indicated by printing in suitable colors or otherwise. Also, window representations, including curtains and drapes and punched-out openings, if desired, may be provided as indicated generally at 17. Pictures may be indicated as at 18 and a fire-place or other article may be represented by printing or otherwise, as indicated 35 at 19. On the bottom 7 of the box section, there may be represented a rug 20 and a portion of a fire-place, as indicated at 21. On the outside surface of the walls, there may be representations of wood siding, as indicated at 22, or any other 40 form of exterior house construction, and on such portions of the box bottom 7 as are outside of the walls, there may be a representation of brick or other flooring, as indicated at 23.

45 It will be seen by reference to Fig. 1 that the walls are so arranged and of such dimensions that the spacing between the front edges of the end walls 10, 10 with respect to each other and with respect to the corresponding end edges of the side wall 9 is such that the various edges 55

referred to will approximately fit within the depending flanges of another inverted box bottom constituting the base or floor portion of another play room. Accordingly, a series of the rooms 5 may be stacked on one another, as clearly shown in Figs. 4 and 5. The close fitting arrangement of the walls of one room within the base of the room immediately above will, of course, serve to maintain the parts in properly aligned 10 assembled relation. Alignment of a plurality of the rooms, stacked on one another, may also be obtained, without regard to the fit of the ends of the various walls within the depending flanges of a box bottom, by reason of the alignment of 15 the depending tongues 13 on the upper edges of the walls of the room below. The depending tongues, which project through the floor, may be flexed slightly as indicated at Fig. 4, so as to overlap the wall portions below, and the tongues 20 of each wall may, of course, be bent to fit alternately on opposite sides of the respective walls of the room below. The cover 24 of one of the boxes may be placed on top of the uppermost room to represent a roof and its uppermost 25 surface may be suitably decorated for this purpose.

The described structure may be made entirely 30 of heavy paper board and because of the firm connections resulting from the tongue and opening connections described and the particular arrangement of the parts, the structure is quite 35 rigid. Also, because of the low cost of the material entering into the construction of the play room, a fairly large sized room may be made for selling at comparatively low prices.

35 The described structure may be changed without departing from the spirit of the invention, the scope of which should be determined by reference to the following claims, the same being construed as broadly as possible consistent with the 40 state of the art.

I claim:

1. In a play room of the class described, the

combination of a box section including depending peripheral flanges, a side wall extending upwardly from said box section adjacent one edge thereof and end walls extending upwardly from said box section and transversely of said side wall, and detachable tongue and opening connections between said side and end walls and between said walls and the box section, the box section and the side wall having openings and the end walls each having tongues depending from their lower edges 10 for engaging the openings in the box section and each end wall also having tongues extending rearwardly therefrom to engage the openings in said side wall, whereby the parts are held together in assembled relation, the end walls being disposed 15 in inwardly and rearwardly inclined relation towards each other so that the tongues on the rear edges thereof are in oppositely inclined relation to the plane of said side wall, thereby, in effect, locking the side wall to the end walls against 20 detachment therefrom by normal rearward force on said back wall.

2. In a play room of the class described, the combination of a box section including depending peripheral flanges, a side wall extending upwardly from said box section adjacent one edge thereof and end walls extending upwardly from said box section and transversely of said side wall, said walls having normally substantially horizontal, coplanar top edges, and detachable connections 30 between said side and end walls and between said walls and the box section, the connections between said walls and box section comprising tongues depending from each of said walls and the box section having openings through which 35 said tongues are adapted to project, said tongues being of sufficient length to extend beyond the lower face of the box section and so as to be adapted to engage the upper marginal portion of the walls of another similar play room disposed 40 thereunder for vertically aligning the play rooms.

DONALD M. WARREN.
